(57) **CLAIM**

The ornamental design for a set of fender flares, as shown and described.

DESCRIPTION

FIG. 1 is a perspective view of a set of fender flares installed on a vehicle.

FIG. 2 is a first perspective view of a front left flare of the set of fender flares of FIG. 1, the front right flare of the set of fender flares being a mirror image thereof.

FIG. 3 is a second perspective view thereof.

FIG. 4 is a front view thereof.

FIG. 5 is a rear view thereof.

FIG. 6 is a top view thereof.

FIG. 7 is a bottom view thereof.

FIG. 8 is a left side view thereof.

FIG. 9 is a right side view thereof.

FIG. 10 is a first perspective view of a rear left flare of the set of fender flares of FIG. 1, the rear right flare of the set of fender flares being a mirror image thereof.

FIG. 11 is a second perspective view thereof.

FIG. 12 is a front view thereof.

FIG. 13 is a rear view thereof.

FIG. 14 is a top view thereof.

FIG. 15 is a bottom view thereof.

FIG. 16 is a left side view thereof; and,

FIG. 17 is a right side view thereof.

The broken lines in the drawings illustrate environment of the set of fender flares, which forms no part of the claimed design.
